UNITED STATES PATENT OFFICE.

ALBERT PATITZ, OF WEST MERIDEN, CONNECTICUT, ASSIGNOR TO BRADLEY & HUBBARD MANUFACTURING COMPANY, OF SAME PLACE.

DESIGN FOR A LAMP-STANDARD.

SPECIFICATION forming part of Design No. 11,941, dated August 10, 1880.

Application filed July 2, 1880. Term of patent 7 years.

To all whom it may concern:

Be it known that I, ALBERT PATITZ, of West Meriden, in the county of New Haven and State of Connecticut, have invented a new 5 Design for a Lamp-Standard; and I do hereby declare the following, when taken in connection with the accompanying drawings and the letters of reference marked thereon, to be a full, clear, and exact description of the same, 10 and which said drawings constitute part of this specification, and represent, in—

Figure 1, side view; Fig. 2, top view of the base below the body.

This invention relates to a design for the 15 base and body of the standard for table-lamps; and it consists in the configuration and ornamentation, as shown in the accompanying illustration, and as hereinafter described.

The outline of the lower section of the base 20 is polygonal, as seen in Fig. 2, the feet A extending from opposite sides at four points, more or less. From this lower section the base rises, first, by a fillet, a, then by convex section B, thence by concave section C to a 25 bead, D. The section B is ornamented by a series of scallops, with honeysuckle between, as seen in Figs. 1 and 2. Section C is ornamented by a series of diamonds and tongues with intermediate scroll-work, as also seen in 30 Figs. 1 and 2. At the bottom and top of the body is a band, E, ornamented by a series of points projecting onto the body with square tongues between. The handles F extend from

the lower to the upper band of the body, gradually expanding in width from the bottom up, 35 terminating in a lancet-shaped tip at the top, with a shoulder, d, at the base of the lancet, the surface of the handle ornamented with Japanese tracery, as shown in Fig. 1.

I claim—

1. The design for lamp-standard, consisting 40 of the polygonal lower section, the feet A extending therefrom, the circular fillet a thereon, the convex section B above, ornamented with a series of scallops and intermediate honeysuckles, and concave section C, ornamented 45 with a series of diamonds and tongues and intermediate scroll-work, as shown in the accompanying illustration.

2. The design for lamp-standard, consisting 50 of the body, with the band at top and bottom, ornamented by a series of points and intermediate square tongues, as shown in the accompanying illustration.

3. The design for lamp-standard, consisting 55 of handles extending from the lower to the upper band of the base, gradually expanding and terminating above in a lancet-shaped point, with an offset or shoulder, d, and the surface ornamented as shown in the accompanying illustration. 60

ALBERT PATITZ.
